BAG OF PAPER OR LIKE MATERIAL AND
THE MANUFACTURE THEREOF

Jan Cornelis Hellema, Zaandam, Netherlands,
assignor to N. V. Papierwarenfabrik Voorheen
Gebrs. Hellema, Zaandam, Netherlands, a
company of the Netherlands

Application March 31, 1938, Serial No. 199,158
In the Netherlands January 31, 1938

1 Claim. (Cl. 229—61)

The present invention relates to bags of paper or like material, which may be coated or impregnated or otherwise treated as may be required, and which for brevity will be referred to as paper.

5 The invention relates particularly to that kind of paper bag which although folding flat when in use. Such bags hitherto have consisted in essence in a single piece or strip of paper, with the longitudinal edges thereof stuck together forming in effect a tube one end of which having been cut, folded and stuck in certain ways to form the bottom. Production in quantity, for example by a continuous mechanical method, is 10 very complicated and requires, particularly for the formation of the bottom a complicated mechanism that is not sufficiently reliable and frequently gives rise to interruptions in the operation of bag making. Moreover the bags when 15 produced have the disadvantage that before they can be filled they have to be opened or extended by hand, or even by the very insanitary method of blowing into them. The present invention seeks to provide a construction of bag and a 20 method of manufacture thereof, avoiding these difficulties.

According to the primary feature of the invention, a paper bag of the kind mentioned, i. e., having a substantially rectangular cross section 25 when open and a flat bottom, has seams (preferably secured by adhesive) along two opposite side walls, and a seamless bottom. Such a bag preferably consists of a blank, which may be a section of strip or like paper, which is doubled upon itself about a transverse fold or a plurality of transverse folds, the longitudinal margins also 30 having folds to form front and back, and opposed side walls respectively, the side walls each being formed by two parts integral with the front 35 and back walls, and united along a seam. Further constructional features, somewhat difficult to discuss without reference to drawing, are included within the invention, as will be made clear hereinafter.

40 45 Further according to the invention, a method of manufacturing paper bags characterised as above, consists in forming a substantially rectangular blank of greater length than twice the height of the desired bag when in use, folding it upon itself about one or more transverse lines simultaneously or previously folding in the longitudinal sides so that opposed sides come edge to edge and uniting such edges preferably by adhesive.

50 55 Further details of the novel method will be-

come clear from the following description of the invention with reference to the accompanying drawing.

Fig. 1 is a perspective view of a paper bag according to the invention in which the front 5 wall is partially cut away.

Fig. 2 shows perspectively a bag according to the invention in one of the stages of its production, viz. shortly before gluing the gumming strip or strips of one half of the blank to the folded 10 longitudinal marginal portions of the other half, after doubling the blank upon itself.

Fig. 3 is a plan view of a blank for the production of a bag as shown in Fig. 1.

Fig. 4 illustrates perspectively the initial folding of the blank.

As appears from Fig. 1 the bag in opened or extended condition has a substantially rectangular cross-section; the two opposite narrow side-walls 1 and 2 of the bag, along each of which runs a gummed seam 11, 21, adjacent the integral bottom 3 are folded inwardly to form triangular pockets 4 and 5 respectively. The lower walls of such triangular pockets are glued to the bottom of the bag as will appear from the following description of the manner of manufacture of the bag.

For manufacturing a bag according to the invention one starts either with a finished blank as shown in Fig. 3 or preferably, with a continuous paper web of which sections are cut off, of a length greater than twice the height of the bag when in use. Of this section, along the longitudinal sides thereof, and if desired before severing the section from the web, strips are cut off along half the length of the section in such a manner that along the other half length there remain laterally projecting gumming strips 6, 7, which subsequently are folded outwardly along the lines 8, 9. As will be readily understood such gumming strips may also be disposed in stepped relation instead of directly opposite each other. From the blank thus obtained the longitudinal portions are subsequently folded inwards about lines 10, 11 running parallel to the longitudinal edges and equidistant therefrom, the triangular regions 12, 13 being previously coated with an adhesive so that these regions during the folding of the longitudinal portions 14, 15 about the lines 10, 11 are glued on to the middle region or bottom 16 of the blank. The gumming strips 6, 7 are thereby presented towards the opposite longitudinal portions 14, 15, all in the manner as shown in Fig. 2. The portions of the centre region 16 coming into contact with the regions 12, 55

13, may alternatively be those to which the adhesive is applied.

In this condition of the blank, three parallel transverse lines of weakness 17, 18 and 19 respectively, are formed in the blank, of which the first is located in the middle of the blank, the remaining two being spaced from said centre line a distance equal to the width of the longitudinal portions 14, 15. Subsequently the inclined lines of weakness 20, 21 and 22, 23 are formed, such lines diverging symmetrically from the two ends of the centre transverse line 17 and running to the points defined by the intersection of the lines 10 and 11 with the two other transverse lines 18, 19. These inclined lines of weakness 15 therefore enclose together with the corresponding portion of the longitudinal lines of weakness 10, 11, the said triangular regions 12, 13. It will be apparent that the lines of weakness 11-23 20 may be formed prior to the application of adhesive.

After the folding of the longitudinal portions 14, 15 and the gluing of the triangular regions 12, 13 on to the centre region 16, the blank in 25 the manner shown in Fig. 2 is folded upon itself about the centre transverse line of weakness 17 and the gumming strips 6, 7 previously being coated with adhesive are glued, or are otherwise fixed, against the opposite marginal portions 14, 30 15, thereby completing the bag. The above described series of operations may be carried into effect by the aid of very simple mechanical means.

A bag thus produced will immediately tend to 35 set itself upon a flat bottom under the pressure of material poured thereinto, in so doing opening itself about the lines of weakness 18, 19 and the inclined lines of weakness 20-23, so that the bag automatically takes up the substantially rectangular cross-sectional formation.

When starting with a blank as shown in Fig. 3 the particular face of the gumming strips 6, 7 and the edges of the marginal portion 14, 15 contact-

ing such strips as also the triangular fields 12, 13 and the corresponding portions of the centre field 16 may be covered with a rubber solution so that such portions, when brought into contact with each other, are stuck together, whilst they will not stick to surfaces not covered with such solution, so that the blanks may be stacked flat without risk.

It will be understood that the invention is not limited to the precise embodiment above described and illustrated in the accompanying drawing, and in particular that the sequence of the various manipulations in making the bag, may be varied at will.

What I claim is:

A collapsible bag of paper or the like forming in open condition a rectangular casing having a flat one-piece bottom and outwardly open triangular pockets adjacent said bottom, said bag comprising in collapsed condition a front and a 20 rear panel integral with and folded upon one another about a transverse center fold, and two side panels having their longitudinal edges secured to the corresponding longitudinal edges of said front and rear panels and each being doubled 25 upon itself inwardly between said front and rear panels about a longitudinal center fold, all said panels being provided with transverse creases parallel to said transverse center fold and at a distance therefrom equal to half the width of 30 said side panels, each of said side panels being provided with two oblique creases running diagonally from the point where the transverse and longitudinal center folds meet to the points where the transverse creases intersect the longitudinal edges of the side panel, the two contiguous triangular portions of each side panel defined by said oblique creases, the panel edges and the transverse center fold being adhered to the inner faces of said front and rear panels, respectively.

JAN CORNELIS HELLEMA.
